(57) CLAIM

The ornamental design for a droplet tablet, as shown and described.

DESCRIPTION

FIG. 1 is a top perspective view of a droplet tablet showing our new design with portions shown in stippling to indicate color contrast;

FIG. 2 is a right end elevation thereof;

FIG. 3 is a left end elevation thereof;

FIG. 4 is a front elevation thereof;

FIG. 5 is a top plan view thereof;

FIG. 6 is a bottom plan view thereof; and,

FIG. 7 is a top perspective view of a modified embodiment of the design shown in FIGS. 1 through 6, the other views being identical thereto apart from the lack of stippling to indicate color contrast.
